TENSION DEVICE

Arthur A. Arnold, Pottstown, Pa., assignor of one-half to Harry Sarfert, Philadelphia, Pa.

Application July 23, 1935, Serial No. 32,760

3 Claims. (Cl. 242—147)

The present invention relates to thread spinning or throwing mechanism and more particularly to a novel device for maintaining a desirable tension upon threads.

Tension devices of the character to which this invention relates have heretofore generally consisted of a spiral wound wire having a vertical length about which the thread is looped and two ends, one of which is seated in a hole in the wooden mounting rail and the other of which is made fast by a screw entering such rail. Since it is necessary to remove and replace these tension devices in order that different kinds of thread may be worked, or for different twisting of threads, the holes in the rail become worn and enlarged. The result is the tension devices work loose, the tension varies, and much trouble develops in consequence.

Some of the objects of the present invention are to provide an entirely new and efficient tension device and mounting therefor; to provide a tension member wherein friction of the moving thread is reduced to a minimum; to provide a tension member wherein variation in the thread tension can be made while the thread is feeding; to provide a mounting for a tension device which becomes a fixed permanent attachment to the tension support rail; to provide a tension mounting wherein provision is made for changing from one tension device to another without removing the mounting from the part to which it is attached; to provide a novel removable and replaceable tension mechanism; and to provide other improvements as will hereinafter appear.

In the accompanying drawing Fig. 1 represents a perspective of a portion of a thread spinning machine equipped with a tension device embodying one form of the present invention; Fig. 2 represents a perspective of the base or support of the tension device; Fig. 3 represents a section on line 3—3 of Fig. 2; Fig. 4 represents a section on line 4—4 of Fig. 2; Fig. 5 represents a plan of one form of tension device particularly for left hand twisting; Fig. 6 represents a front elevation of the tension device of Fig. 5 connected to the base or mounting; Fig. 7 represents a front elevation of the form of tension device, for rise with right hand twisting, connected to the novel base or mounting; and Fig. 8 represents a plan of the base or mounting used as a support for a thread guide of ordinary construction.

Referring to the drawing one form of the present invention consists of a base 10 arranged to support and hold a tension member 11 for use where the thread twist is to the left, or a ten-

sion member 12 for use where the thread twist is to the right, or a centering guide 13 for a straight run of thread. The base 10 in the preferred form comprises a substantially cube-shaped body 14 having flanges 15 projecting from two opposite sides to provide suitable areas for holes 16 through which screws 17 or like fastening can be passed to permanently secure the base 10 in its proper position upon the rail 18 of the twisting machine. It is to be understood that one such base 10 is fixed to the rail opposite each take-up roll 20. The body 14 is provided with a through bore 21 extending from one side thereof to the other and having its ends opening respectively into two face grooves 22 and 23. Each of these grooves extends from the front of the body 14 to a point beyond where the bore 21 is met, and the size of each groove is such as to snugly receive and seat the supporting leg of the complementary tension device. A socket 24 is bored into the body 14 from the front and intercepts the bore 21 at a point coincident with a threaded hole 25, so that a set screw 26 becomes a common fastening means for any one of three different devices used one at a time.

The tension member 11 consists of a wire having one end in the form of a straight leg 27 and the other end in the form of a free end half loop 28, while the intermediate portion is in the form of a downwardly tapering spiral 30. The leg 27 is turned in the direction such that when it is within the bore 21 the wire seats in the groove 22. The convolution of largest diameter joins the leg 27 by a length 31 and the successively smaller convolutions extend downwardly well below the plane of the leg 27 to ultimately form a guide loop 32 from which the thread receiving shank 33 rises in reverse direction. Preferably the shank 33 extends upwardly through the spiral 30 and at an angle 40 to its axis so that the thread 29 enters and leaves the tension device at points out of direct alinement. This angular inclination of the shank 33 to the direction of thread feed permits the thread to ride back and forth as the tension varies so that the thread has less frictional wear than when feeding about a wire which coincides in direction with the direction of thread feed. Furthermore since the half loop 28 terminates in a free end it is possible to change the number of wraps about the shank 33 at will, while the machine is in operation.

The tension member 12 is formed just the reverse from the member 11 but embodies all the novel features of construction described

in connection with the member 11. Its leg 34 therefore turns in the direction to enter the bore 21 from the side necessary to seat the wire in the groove 23. The shank 35 is inclined with respect to the direction of travel of the thread for the purpose above described. Repetition of the description as to the spiral and other details are believed unnecessary.

In Fig. 8 the base 10 is shown receiving and supporting a centering guide 36 of usual shape, which is held in place by the same set screw 26 used for holding a tension device when such is substituted.

While only a single form is shown in which this invention may be embodied, it is to be understood that the invention is not limited to any specific construction, but might be applied to various forms without departing from the spirit of the invention or the scope of the appended claims.

Having thus described my invention, I claim:

1. A base support for a tension device consisting of a body having a bore to receive the end of a tension wire and a groove angularly disposed to said bore and communicating with said bore to seat a portion of said wire, means

to hold said wire end in said bore, and means to fasten said body to a fixed part of a thread spinning machine.

2. A base support for a tension device consisting of a body having a bore therethrough and two grooves respectively at opposite sides of said body communicating with said bore, said grooves lying in a horizontal plane intercepting said bore, means to hold one end of either of two tension wires in said bore whether the wire is in one or the other of said grooves, and means to fasten said body to a fixed part of a thread spinning machine.

3. A base support for a tension device consisting of a body having a bore therethrough, two grooves respectively at opposite sides of said body communicating with said bore, and a hole communicating with said bore, said grooves lying in a horizontal plane intercepting said bore, said bore and one groove serving to seat a tension wire, and said hole serving to seat a thread guide, a fastening means arranged to clamp a wire in either said bore or hole, and means to fasten said body to a fixed part of a thread spinning machine.

ARTHUR A. ARNOLD.
